(57) **CLAIM**

We claim the ornamental design for an exercise device, as shown and described.

DESCRIPTION

FIG. 1 is a front perspective view of the exercise device in a lowered position, showing our new design.

FIG. 2 is a rear perspective view of FIG. 1;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view of FIG. 1;

FIG. 7 is a bottom plan view of FIG. 1;

FIG. 8 is a right-side elevational view thereof in a raised position, the left-side elevational view being a mirror image thereof; and,

FIG. 9 is a front elevational view of FIG. 8, the rear elevational view being a mirror image thereof.

The broken lines in the drawings illustrate portions of the exercise device that form no part of the claimed design.
